(57) CLAIM

The ornamental design for a combined street sign and post, as shown and described.

DESCRIPTION

FIG. 1 is a front elevational view of the combined street sign and post;

FIG. 2 is a rear elevational view;

FIG. 3 is a side elevational view taken from the right side of FIG. 1;

FIG. 4 is a top plan view of FIG. 1; and,

FIG. 5 is a bottom plan view of FIG. 2.

In the drawings, the broken lines represent environmental structure forming no part of the claim.
